UNITED STATES PATENT OFFICE

167,403

CASE FOR ELECTRICAL TESTING INSTRUMENT

Austin D. Hopkins, Kalamazoo, Mich., assignor
to The Wigginton Company, Kalamazoo, Mich.

Application August 14, 1951, Serial No. 16,274

Term of patent 14 years

(Cl. D52—1)

To all whom it may concern:

Be it known that I, Austin D. Hopkins, a citizen of the United States, residing at Kalamazoo, in the county of Kalamazoo and State of Michigan, have invented a new, original, and ornamental Design for Case for Electrical Testing Instrument, of which the following is a specification, reference being had to the accompanying drawing, forming a part hereof.

Fig. 1 is a front elevational view of the case for an electrical testing instrument, showing my new design.

Fig. 2 is a side elevational view thereof.

Fig. 3 is a bottom plan view thereof.

Fig. 4 is a top plan view thereof.

I claim:

The ornamental design for a case for electrical testing instrument, substantially as shown.

AUSTIN D. HOPKINS.
